UNITED STATES PATENT OFFICE.

CHARLES JAMES HIBBERD, OF ANNAPOLIS, MARYLAND.

BLOCK AND TACKLE.

SPECIFICATION forming part of Letters Patent No. 379,113, dated March 6, 1888.

Application filed November 25, 1887. Serial No. 256,144. (No model.)

To all whom it may concern:

Be it known that I, CHARLES JAMES HIBBERD, a citizen of the United States, residing at Annapolis, in the county of Anne Arundel 5 and State of Maryland, have invented certain new and useful Improvements in Block and Tackle; and I do hereby declare the following to be a full, clear, and exact description of the invention, such as will enable others skilled 10 in the art to which it appertains to make and use the same.

Referring to the accompanying drawings, Figure 1 represents the general arrangement of a block and tackle embodying my invention. 15 Fig. 2 is an enlarged detailed view of my improved pulley-block with one of the face-plates removed. Fig. 3 is a detail of the pivoted pulley-carrying lever.

My invention relates to devices for hoisting 20 and lowering heavy articles, and is especially applicable to purchase-blocks, such as are used in machine-shops or in connection with "boat-falls, &c.;" and my invention consists in the improved construction and combination of 25 devices which I shall hereinafter fully describe and claim.

To enable others skilled in the art to make 30 and use my invention, I will now describe its construction and indicate the manner in which the same is carried out.

In the said drawings, A represents the usual pulley-block, to which one end of the rope or cable B is secured in any appropriate manner, said rope or cable passing therefrom to and 35 under a pulley journaled in a block, B', as shown in Fig. 1.

In the top of the block A, upon the bar A', is suitably secured the usual swivel, C, and between the face-plates *a* of the block A, and in 40 the upper portion and to one side of the vertical center of the same, is secured a recessed block, G, having downwardly-extending lugs *b*, the purpose of which will be hereinafter fully disclosed.

Between the face-plates are pivotally secured 45 the arms *c* of a bifurcated lever, D, said arms being contracted at one end and uniting to form the long arm of the lever, and also to form a guide or opening through which the 50 free end of the rope or cable is passed.

Within the lever D, and at points between the arms and upon each side of the pivotal center of the lever, pulleys E E' are loosely mounted, the rope or cable, after extending from the lower pulley-block, B, being passed over said pulleys E E', and has its free end directed to and passed through the guide or opening in the lever between the pulley E and the end of said lever. 55

In operating my device, as when raising a heavy weight, the strain or power is brought 60 to bear upon the pulley E, to cause the extended portion of the lever to be depressed and the opposite portion carrying the pulley E' to be elevated. When in this position, 65 which is the normal position in elevating the weight, the rope or cable is permitted to run freely through the block; but the instant the pull or power is removed from the drawing or free end of the cable the weight acting upon 70 the pulley E causes the pivoted lever to be tilted in an opposite direction, whereby the rope or cable is tightly clamped between the pulley E and the downwardly-extending lugs or arms *b* of the block G, as seen in dotted lines 75 in Fig. 2. In this latter position the rope in the groove of the pulley E will be forced into the recess in the block G, and also tightly pinched at two points against the lower edges of the arms *b*. The said rope cannot possibly 80 slip, for the greater the weight suspended the more tightly will the cable be gripped between the pulley and block.

If it be desired to lower a heavy article, the cable may be caused to pay out slowly and 85 with absolute safety by simply drawing upon the cord or connection *e*, attached to the long arm of the lever D, until the pressure on the cable is released sufficiently to permit a regular and safe paying out of said cable and the 90 consequent lowering of the article or weight.

By reason of the above construction I am 95 enabled to provide a simple and effective means for elevating heavy articles, whereby, should the cable slip, the descent of the article would be instantly checked; or, if it be desired to suspend said article, the same may be effected automatically and with perfect safety by releasing the power or "pull" upon the cable. 100

Having thus described my invention, what I claim as new, and desire to secure by Letters Patent, is—
An improved block and tackle consisting of the pulley-blocks A and B', the cable B, the bifurcated lever D, pivoted within the block A and having the pulleys E E', the bar A', having the swivel mounted thereon, and a recessed block in the pulley-block A between said lever and bar and at one side of the vertical center of said pulley-block, said recessed

block having two downwardly-extending arms adapted to pinch the cable at different points, whereby said cable may be securely held; as herein described.

In testimony whereof I affix my signature in presence of two witnesses.

CHARLES JAMES HIBBERD.
